Primary Examiner — Sheryl Lane*Assistant Examiner* — Emily A Caven(74) *Attorney, Agent, or Firm* — Xuan Zhang(57) **CLAIM**

The ornamental design for a pet feeding bowl, as shown and described.

DESCRIPTION

FIG. 1 is a top perspective view of a pet feeding bowl showing my new design;

FIG. 2 is a top view thereof;

FIG. 3 is a bottom view thereof;

FIG. 4 is a left view thereof;

FIG. 5 is a right view thereof;

FIG. 6 is a rear view thereof;

FIG. 7 is a front view thereof; and,

FIG. 8 is a bottom perspective view thereof.

The broken lines in the drawings are included for the purpose of illustrating environmental structure and forms no part of the claimed design.

1 Claim, 8 Drawing Sheets(56)
